METER FOR TESTING ELECTRONIC COMPO- NENTS, INCLUDING TRANSISTORS, DIODES AND OTHER SOLID STATE ELECTRONIC DEVICES

Louis W. Erath, Houston, Tex., assignor to Test Equipment Corporation, Houston, Tex., a corporation of Texas

Filed Sept. 12, 1962, Ser. No. 71,663

Term of patent 14 years

(Cl. D52—6)

Fig. 1

Fig. 2

Fig. 3

Fig. 4

Fig. 5

Fig. 6

FIG. 1 is a perspective view of a meter for testing electronic components, including transistors, diodes and other solid state electronic devices, taken from the front and one side, showing my new design.

FIG. 2 is a bottom view of the meter.

FIG. 3 is a back view of the meter.

FIG. 4 is a plan view of the meter.

FIG. 5 is a perspective view from the rear of the meter.

FIG. 6 is an elevational view of the front of the meter.

I claim:

The ornamental design for a meter for testing electronic

components, including transistors, diodes and other solid state electronic devices, substantially as shown.
